SUPERVISORY CONTROL SYSTEM

Application filed August 9, 1927. Serial No. 211,681.

My invention relates to selective signalling systems in which apparatus units are selectively controlled and supervised from a remote station.

5 An object of my invention is to provide synchronously operated relay chains located at the two remotely disposed points for synchronously switching signalling lines connecting said points to equivalent units.

10 Another object of my invention is to provide circuit arrangements for stepping relay chains, located at two remote points, in synchronism by means of a code.

Another object of my invention is to provide 15 means for identifying each selected position before completing the selection.

Another object of my invention is to provide a method of operating a synchronous selecting system which includes the steps of 20 preparation, identification and completion of the selected prepared circuit.

Another object of my invention is to provide 25 circuit arrangements for releasing the selectors when a non-synchronous condition arises (without the use of additional signalling lines).

Another object of my invention is to provide 30 manual means for instantaneously restoring the selecting apparatus to normal, at any time, employing no additional signalling lines.

Still another object of my invention is to provide means for employing the same signalling line for control, supervision, drive 35 and reset.

Another object of my invention is to provide 40 circuit arrangements for operating relay chains at two remote points in synchronism, employing only uniform fast-type relays.

Another object of my invention is to provide 45 a method of selective signalling which includes preparation, identification of the selection, completion of the selection and code operation of the selected unit.

Still another object of my invention is to provide 50 circuit arrangements whereby the signalling lines are maintained open until identification of the selection.

55 There are other objects of my invention

which, together with the foregoing, will appear in the specification which follows.

The supervision and control of substation power apparatus from a dispatcher's office introduces problems not present in any other 55 type of signalling systems.

In most of the existing signalling systems, a small-percentage error in selection is usually considered permissible. No serious consequence results from an occasional error 60 in a telephone, telegraph or other signalling system. On the other hand, in supervisory control, each operation is important, and the effect may be of serious moment. An incorrect operation may result in damage more 65 costly than the system itself. For this reason, it is necessary that the selecting system employed be infallibly accurate.

Another vital difference between supervisory-control selecting systems and other 70 selecting systems is found in the fact that, in the former systems, it is desirable to obtain direct control of the selected unit and that such control be held by the dispatcher indefinitely. In other signalling systems, a selection 75 is usually made in order to perform a single operation, such as to ring a called party in a telephone system. In supervisory control, on the other hand, after having selected an apparatus unit, such as a circuit breaker, 80 further selective operations, such as opening and closing the circuit breaker may be desirable, and, since further selections may be performed a number of times, it is important that the selected unit be retained under control of the dispatcher until he restores the 85 selectors to normal.

To accomplish this latter purpose, the selecting system employs a start-stop synchronous operation in which the signalling lines 90 are switched synchronously at the two remote stations in a step-by-step fashion and stopped at the desired selected point. Direct connections of the selected unit are therefore obtained over the signalling lines. 95

In this type of synchronous selection, however, the selected units are subjected to inductive surges induced on the signalling line. Heretofore, this difficulty has been corrected by interposing equipment between the select- 100

ed units and the line. This equipment, however, is both expensive and renders the system involved.

In order to overcome this difficulty, the present invention employs a code means for stepping the chains synchronously, so that each position is selected by the accuracy of a code, while the advantage of direct connection is obtained in that the selectors are stopped as in a synchronous start-stop system.

In practicing my invention, I provide circuit arrangements for synchronously stepping relays at two remote points, equivalent relays at each station being stepped by an individual code. Signalling lines connecting the two remote points are stepped from point to point by synchronous energization of the relays mentioned above for sequentially connecting apparatus units at one point to their individual operating means at the other or remote station. Selected units are operated by code combinations of impulses.

A checking circuit is provided for identifying the selections made, and a reset is arranged to operate over the signalling lines.

Referring to the drawings, Figs. 1 and 2 are diagrams disclosing the apparatus and circuits at the office, and

Figs. 3 and 4 are diagrams disclosing the apparatus and circuits at the substation.

Fig. 5 is a diagram showing the order and relations of the relays as they are energized and deenergized during one cycle of operations.

In general, my invention comprises a bank of selecting relays 211 to 220, located at the office and a bank of selecting relays 311 to 320, located at the substation for synchronously switching two signalling lines 298 and 299, by means of code impulses from key to key, 150 and 156, and apparatus unit to apparatus unit, 420 and 430.

Referring more particularly to Fig. 1, 150 and 156 are individual operating means, in this case, twist-type keys, and associated therewith are individual stop keys 151 and 157. Supervisory lamps 152, 153, 158 and 159 indicate the condition of their individual remote apparatus unit. Disagreement lamps 154 and 160 are illuminated when the position of the individual twist key and associated apparatus unit are not in accord. The position of the selectors is shown by the lamps 155 and 161. Key 167 is a master control key which controls the supply of energy over the signalling line for performing an operation following a selection. Lamps 168, 170 and 171 indicate the condition of the system, that is, whether it is at rest or in operation and, if in operation, whether in synchronism or out of synchronism.

The relays 104 to 113 are the operation-control relays which function after a selec-

tion has been completed for transmitting an operating code.

Referring now more particularly to Fig. 2, the selecting relays 211 to 220 are individual to the keys 150 and 156 and are operated sequentially by the switching relays 201 to 210, which function to transfer the drive-line impulses to successive selecting relays. By novel circuit arrangements, the switching relays deenergize as soon as the necessary switching operations have been performed. This eliminates the difficulties encountered when a large number of these relays are simultaneously in an energized condition. Relays 232 and 233 are supervisory code-receiving relays. All supervisory signals received operate these relays which, in turn, relay control to the proper individual supervisory lamps.

The relays 221 to 231 are the driving and checking relays which function to operate the drive circuit for sequentially energizing the selecting relays. The relay 234 is the reset relay operatively responsive to a non-synchronous condition for restoring the selectors to normal.

Referring more particularly to Fig. 3, selecting relays 311 to 320 are energized sequentially in synchronism with the selecting relays 211 to 220 by driving impulses received by the driving relays 321 to 331 and relayed, in turn, to each succeeding switching relay by relays 301 to 310. Relays 332 and 333 function in response to a prolonged opening or deenergization of the drive line to restore the relays to normal.

Referring more particularly to Fig. 4, circuit breakers 420 and 430 are illustrative of the apparatus units employed at the substation, although it is to be understood that any equipments of other types may be the selected units.

Relays 412 to 417 are individually operating relays for the circuit breaker 420, and similar relays 422 to 427 are individual to circuit breaker 430. The relays 402 to 409 are the operation-control code-receiving relays which respond to the code transmitted by the relays 104 to 113, following a selection.

Before going into a detailed description of the operation, a general description of the steps which take place in making a selection will be given. Normally, a holding circuit is completed over the control line 298. The first operation, either the closing of a key manually at the office or the automatic operation of a circuit breaker at the substation, opens the holding circuit. A circuit is thereupon completed over the drive circuit 398.

The impulse transmitted over the drive circuit is of a predetermined polarity and is relayed to energize the first selecting relay 211 at the office and relay 311 at the substation. The energization of the selecting re-

lay 211 at the office and relay 311 at the substation completes a check impulse of a predetermined polarity and over a predetermined line, in this case, the supervisory line 299.

5 Unless the correct selecting relays have been energized, both at the office and at the substation, the check impulse will not be completed, since it finds its circuit over the contacts of the associated selecting relays at the 10 two stations. During this period, although the selecting relays have been energized, the supervisory and control lines 298 and 299 are open circuited. The supervisory line, as a matter of fact, functions at this time as a 15 check signalling line. If the checking impulse is found to be correct, that is, a checking circuit is completed, the relay 230 energizes and completes the circuit of the control and supervisory lines 298 and 299 to the selecting relays at the two stations.

20 A circuit is now completed from the individual key at the office over the first selecting relay to the apparatus unit over the first selecting relay at the substation and, if the stop key is opened, a closed or tripped code may be 25 transmitted for operating the circuit breaker.

25 In order to better understand the invention, a more detailed description of the operation which now takes place will be given. The operations about to be described will best be understood if the Figure 5 is studied at the same time as the description is read.

30 Although the relays are shown connected to apparently different batteries, it will be understood that this is used for convenience in illustration and that, in actual practice, only one battery shown in the lower right-hand corner of Fig. 2 is used. Thus, the relay 104, for example, is connected to the negative side of the battery shown in the lower right-hand corner of Fig. 2. Similarly, the batteries shown in Figs. 3 and 4 are shown for convenience in illustration and it will be understood that a single battery is used in practice, as shown in the lower left-hand corner of Fig. 3. The positive terminals of each of these batteries are connected to a common return circuit which is the return line for all of the circuits extending between the two stations.

35 Normally, with the apparatus at rest, a circuit is completed from the positive side of the battery at the office through the winding of relay 222, the back contact and armature 286, conductor 298, armature 366 and its back contact, through the winding of relay 330 and battery, to ground. This circuit, it will be noted, is completed over the back contacts of relays 230 and 322. If relay 230 is energized 40 by the closing of a start key at the office, or relay 322 is energized as a result of an automatic operation, this holding circuit will be opened to start the selectors into operation, as will hereinafter be described in more detail.

45 As a result of the energization of the relay 222 at the office, an energizing circuit is completed for the lamp 168 from ground over armature 268 and its front contact, conductor 196 and, through the lamp 168 and battery, to ground. The illumination of the lamp 168 indicates to the dispatcher that the set is at rest. The energization of the relay 330 at the substation prepares a start circuit for setting the apparatus into operation, responsive to an 50 automatic movement of the circuit breaker.

55 It will be assumed that the dispatcher desired to close the circuit breaker 430 at the substation. In order to do this he will momentarily operate the start key 169 to its closed position. A circuit will thereupon be completed for the relay 230 from ground through battery, the winding of the relay 230, back contact and armature 267, conductor 198, closed contacts of the key 169, conductor 197, and, through the back contact and armature 266, to ground.

60 The energization of the relay 230 at the office opens the original holding circuit over the conductor 298 at armature 286. As a result of the opening of the holding circuit, the relay 222 at the office and the relay 330 at the substation are deenergized. The deenergization of the relay 222 at the office opens the originally traced circuit for the lamp 168 at armature 268 and its back contact and closes a circuit for the lamp 170 over a circuit from ground, armature 268 and its back contact, conductor 198, and, through the lamp 170 and battery, to ground. The lamp 168 is extinguished and the lamp 170 is illuminated and the dispatcher is thus informed that the 65 system is started into operation.

70 A further result of the deenergization of relay 222 is to complete an energizing circuit for the relay 230 which by-passes the original starting key at armature 268, the circuit being completed from ground through battery and through the winding of relay 230, back contact and armature 267 and back contact 75 and armature 268 to ground.

75 Simultaneously with the deenergization of the relay 222 at the office, the relay 330 at the substation is deenergized upon the opening of the holding circuit.

80 With the armature 385 moved to its back position, an energizing circuit is completed for the relay 322 from ground over armature 385 and its back contact, winding of relay 322 and battery to ground.

85 The energization of the relay 230 at the office functions to switch the control and supervisory lines to a prepared selecting circuit over the armatures 286 and 287, respectively, and completes the first drive circuit over 90 armature 288 at the office. The energization of the relay 322 at the substation likewise switches the control and supervising lines to selecting circuits over armatures 366 and 367 and completes the first drive circuit over 95 100 105 110 115 120 125 130

armature 368. A circuit is thereupon completed from ground through battery back contact and armature 273, through the winding of relay 225, back contact and armature 272, armature 291 and its back contact, front contact and armature 288, back contact and armature 269, armature 290 and its back contact, the drive line 398, back contact and armature 365, armature 368 and its front contact, through the winding of the relay 327 to armature 381 and its back contact, to ground.

As a result of the first driving impulse just traced, the drive relays 225 at the office and 15 327 at the substation are energized. The energization of the drive relay at the office completes an energizing circuit for the first selecting relay 211 from ground over armature 274 and its front contact, conductor 175, 20 back contact 121, conductor 184, and, through the winding of relay 211, to battery and ground. The circuit, it will be noted, is completed over the back contact of armature 121, controlled by relay 103. As soon as the 25 selecting relay is energized, it prepares a circuit for the succeeding selecting relay. In order to prevent the succeeding relay from energizing at this time, its energizing circuit is opened at armature 121, as will be described 30 in more detail hereinafter.

The energization of the selecting relay 211 completes a locking circuit for itself over a circuit from ground through battery, through the winding of relay 211, its first extreme left-hand contact, back contact and armature 236, back contact and armature 238, conductor 173, and back contact and armature 265 to ground.

As a result of the energization of the drive relay 327 at the substation, an energizing circuit is completed for the first selecting relay thereat from ground over armature 379 and its front contact, armature 382 and its back contact, conductor 394, back contact and armature 484, conductor 395 and through the 45 winding of relay 320 to battery and ground.

The energization of the first selecting relay 320 completes a locking circuit for itself from ground through battery and through the winding of relay 320 and its first contact, 50 back contact and armature 362, back contact and armature 358, conductor 392, conductor 497 and back contact and armature 385 to ground.

The first selecting relay at the office and 55 the substation are now energized. It will be noted that the first drive impulse was completed from negative battery at the office and over the drive line 398 to positive battery at the substation. Attention is called to this 60 fact because the drive impulses, it will be found upon further analysis, remain the same for the first four selections and then the polarity is reversed for the next four selections.

Upon the energization of the first selecting 65 relay 211 at the office and the selecting relay

320 at the substation, a checking circuit is completed from ground through battery, the winding of relay 228, the third contact of the relay 211, back contact and armature 270 through the winding of relay 227, armature 281 and its back contact, the 4th contact of the relay 211, back contact and armature 284, front contact and armature 287, armature 289 and its back contact, conductor 299, back contact and armature 364, armature 367 and its front contact, armature 370 and its back contact, the 4th contact of the relay 320, back contact and armature 372 and through the winding of relay 325, and the 3rd contact of the relay 320 to ground. This is the check circuit which will be completed only after the selecting relay 211 at the office and the selecting relay 320 at the substation are energized. If the check circuit above traced is completed, this is an indication that the correct selecting relays have been energized at the office and at the substation and the selection prepared by the energization of the relays may thereupon be completed.

The relay 228 in the check circuit traced above is a low-resistance relay and fails to operate over the circuit traced. It functions to open the check circuit to give an indication at the office when two succeeding selecting relays at the same station energize simultaneously, in which case, as will be described in more detail hereinafter, sufficient current passes through this relay to energize it. The relay 227, energized in the checking circuit traced above, operates to complete an energizing circuit for the relay 226 over the armature 280 and its front contact.

The energization of the relay 226 completes a locking circuit for itself from ground through battery, winding of relay 226, front contact and armature 277, and front contact and armature 275 to ground.

A further result of the energization of relay 226 is to complete an energizing circuit for the relay 229 from ground over the armature 275 and its front contact, armature 278 and its front contact, armature 282 and its back contact, through the winding of relay 229 and battery to ground.

The energization of the relay 229 switches 115 the control and supervisory lines 298 and 299 from their checking position to their operating position. The above-described operations, it will be noticed, take place only after the position of the selecting relays at 120 the office and at the substation have been checked or identified.

At the substation, the energization of the check relay 325, following the energization of the selecting relay 320 over the circuit 125 traced above, completes an energizing circuit for the relay 326 from ground through battery, winding of relay 326, front contact and armature 375, the 5th contact of the relay 320 to ground. The energization of the 130

relay 326 completes an energizing circuit for the relay 323 from ground through battery, the winding of relay 323, back contact and armature 373, front contact and armature 378, armature 377 and its front contact, front contact and armature 375, through the 5th contact of selecting relay 320 to ground.

The energization of the relay 323 takes place simultaneously with the energization 10 of the relay 229 and both occur only if the correct checking impulse has been transmitted. Upon the energization of the relays 229 and 323, the supervisory line 299 at the substation is extended over the back contact 15 of armature 364, front contact of armature 367 and 370, conductor 493, armature 437 and its back contact, conductor 490, over the 6th contact of the selecting relay 320 to conductor 396 and armature 463 of the individual 20 circuit breaker 420, while at the office, the supervisory line 299 is extended over the armature 289, armature 287 and its front contact, armature 284 and its front contact, conductor 192, the armature 124 and its back 25 contact, back contact and armature 125, armature 131 and its back contact, conductor 186, to the 7th contact of the selecting relay 211, conductor 179, armature 116 and its back contact, conductor 188 and through 30 the winding of relay 232 to ground.

The circuit just traced assumes that the previous supervisory signal for this point was the same, that is, a tripped-circuit-breaker condition. The relay 101 individual to 35 the first circuit breaker will then be deenergized, as will be explained in more detail hereinafter. The armature 116 will be on its back contact. The relay 232 will not be energized, as there was no battery in the 40 circuit traced. An energizing circuit for the lamp 153 is completed from ground over armature 115 and its back contact and through the lamp 153 to battery and ground. Lamp 153 burns green and indicates to the 45 dispatcher that the circuit breaker is open.

If, however, the previous supervisory signal had been a closed supervisory signal, the relay 101 would have been energized and locked in a manner to be described in more 50 detail hereinafter. The supervisory signal would then have followed upon the opening of the circuit breaker and would have been completed over armature 116 and its front contact, conductor 187, and through the 55 winding of relay 233 to battery and ground, the first part of the circuit being the same as that traced above.

The energization of the relay 233 would have provided a shunt circuit for the locking 60 battery of relay 101 from ground over armature 294 and its back contact, front contact and armature 296, the last contact of the selecting relay 211, conductor 178 and through the armature 114 to battery and 65 ground. As a result of this circuit, the lock-

ing circuit of the relay 101 would have been opened and relay 101 would have become deenergized to complete the above-traced circuit for the lamp 153, indicating to the dispatcher that the circuit breaker has opened. 70

Referring now again to the selecting operations, a further result of the energization of the relay 229, following the correct checking impulse transmission, is to complete an energizing circuit for the relay 223 over a circuit from ground through battery, winding of relay 223, armature 285 and its front contact, conductor 189, the closed contact of the stop key 151, conductor 181, the 5th contact of the first selecting relay 211 to ground. 75

The completion of the circuit depends, of course, upon the fact that the stop key individual to this point has not been operated. Not only is this circuit completed over the contact of the key, but also over the front contacts of the check relay and selecting relay. The relay, therefore, must be energized, that is, a selection must have been made before this operation which is preparatory to the succeeding selection, can be completed. 80 If the stop key has been operated to its open position, the stepping operations traced thus far will stop and no further selecting relays will be energized until the stop key is again released to close its contact 85 at 151.

The energization of the relay 223 completes a locking circuit for itself from ground through battery, winding of relay 223, front contact and armature 271, and over the conductor 189 to ground over the circuit traced above. 90

A further result of the energization of the relay 223 is to open the circuit of the check relay 227 at armature 270 which thereupon deenergizes and opens the original energizing circuit of the relay 226 at armature 280. The energization of the relay 223 also opens the drive circuit at armature 272 and thereby 100 deenergizes the drive relay 225. 105

Attention is called, at this time, to the fact that control and supervisory operations take place while the drive circuit is energized, and the preparation for the stepping operations takes place by the opening and further closing of the drive circuit during a non-operating control and supervisory period. This is an important feature of this system, since, by maintaining the drive circuit energized during the operating period, it becomes possible to detect non-synchronous conditions and restore the apparatus to normal without the need of further signalling lines. 110

The above-mentioned detection and restoration become possible by reason of the fact 115 that, at no time, should the drive line be opened for a very long period of time, since it is only opened momentarily during the stepping periods. If the apparatus is brought to a stop for any operating pur- 120

poses, the drive line is closed. Wherefore, if the drive line opens for a period longer than a predetermined reasonable stepping time, it is due to some difficulty or trouble in 5 the system and this extra long open period can then be employed to automatically reset the apparatus to normal.

If, on the other hand, trouble should occur when the drive line is closed, it is only 10 necessary for the dispatcher to open the drive line and keep it open for an interval of time, whereupon the apparatus is restored to normal. This will be described in more detail hereinafter.

15 The above description of the operation has now been traced through a complete cycle. With the drive line opened at armature 272, the relay 225 at the office and 327 at the substation are deenergized. The deenergization 20 of the relay 225 at the office completes an energizing circuit for the first switchover relay 201 from ground through battery, winding of relay 201, the second contact of selecting relay 211, and back contact and armature 25 274 to ground.

The energization of the relay 201 completes a locking circuit for itself from ground through battery, winding of the relay 201, front contact and armature 236, back contact 30 and armature 238, and back contact and armature 265 to ground.

A further result of the energization of relay 201 is to complete an energizing circuit for the relay 103 from ground through battery, winding of relay 103, conductor 174, front contact and armature 235, and back contact and armature 265 to ground.

The energization of the relay 103 completes a locking circuit for itself from ground 40 through battery, the winding of relay 103, front contact and armature 120, conductor 173 and back contact and armature 265 to ground.

The energization of the relay 103 opens the 45 original energizing circuit for the first selecting relay 211 at armature 121 and completes an energizing circuit for the relay 164 over armature 122 and its front contact.

The energized relay 164 completes a locking circuit for itself over armature 166 and the key 162 and completes a circuit for the buzzer 163 over armature 165. The dispatcher is thus advised that the set has been started 55 into operation. Should he be away from his desk when the set is started into operation, due to an automatic movement of a circuit breaker, his attention is thus called to the fact that a change has taken place, and he will immediately return to his desk to find out 60 what operation has taken place. The buzzer continues until he operates the key 162 in order to open the locking circuit of the relay 164.

The energization of the relay 201 switches 65 the selecting relay circuit from the drive re-

lay armature to the relay 212 over the armature 237 preparatory for the next selecting impulse. At the substation, the deenergization of the relay 327 completes an energizing circuit for the switchover relay 310 from ground through battery, winding of relay 310, second contact of the relay 320 and back contact and armature 379 to ground.

The relay 310 locks itself over a circuit from ground through battery, winding of relay 310, front contact and armature 362, back contact and armature 358, conductor 392, conductor 497 and back contact and armature 385 to ground.

80 The energization of the relay 310 completes an energizing circuit for the relay 401 from ground through battery, winding of relay 401, conductor 393, front contact and armature 361, conductor 392, conductor 497 and back contact and armature 385 to ground. The energization of the relay 401 completes a locking circuit for itself over armature 432 and conductor 497, as traced above.

85 The energization of the relay 401 opens the original energizing circuit for the first selecting relay 320 at armature 434 and transfers the starting circuits of all the apparatus units to the reset relay 410 over the front contact of armature 433, as will be described in more detail hereinafter.

90 The energization of the relay 310 opens the locking circuit of the selecting relay 320 at armature 362 and its back contact and prepares an energizing circuit for the next selecting relay 319 at armature 363 and its front contact.

95 Returning now to the operations at the office, a further result of the deenergization of the drive relay 225 at the office is to open the locking circuit for the relay 226 and the energizing circuit for the relay 229 at armature 275. The signalling lines are now restored to their original positions for first transmitting a check impulse.

100 Upon the deenergization of the selecting relay 211, the locking circuit of the relay 223 is opened at its fifth contact. The deenergization of the relay 223 again completes an energizing circuit over the drive line for the relay 225 at the office and relay 327 at the substation, the circuit being completed from battery at the office to ground at the substation.

105 Upon the energization of the relay 225 at the office, an energizing circuit is completed for the second selecting relay 212 over a circuit from ground through armature 274 and its front contact, the front contact and armature 237 and through the winding of relay 212 and battery to ground.

110 The energization of the second selecting relay 212 completes a locking circuit for itself from ground through battery, the winding of relay 212, the first contact of the relay 212, back contact and armature 239, back 115

contact and armature 241 and back contact and armature 265 to ground.

At the substation, the energization of the drive relay 327 completes an energizing circuit for the second selecting relay 319 over a circuit from ground through armature 379 and its front contact, armature 382 and its back contact, front contact and armature 363 and through the winding of relay 319 to battery and ground.

With the second selecting relay at the office and that at the substation energized, a check circuit will be completed from ground over the third contact of the selecting relay 212, 15 the back contact and armature 270 through the winding of relay 227, armature 281 and its back contact, the fourth contact of the selecting relay 212, back contact and armature 284, front contact and armature 287, 20 armature 289 and its back contact, conductor 299 and back contact and armature 364, armature 367 and its front contact, armature 370 and its back contact, fourth contact of the selecting relay 319, back contact and armature 372, 25 through the winding of relay 325, the third contact of the selecting relay 319 and through the winding of relay 324 to battery and ground.

It will be noted from the above that each 30 selecting relay, upon energization, prepares a circuit for its individual switchover relay and that, upon the opening of the drive circuit, the switchover relay energizes, locks itself up, opens its individual selecting relay 35 and prepares a circuit for the next selecting relay.

Upon the next energization of the drive line, the impulse is thus relayed to the succeeding selecting relay. By this arrangement, a positive opening of the previously 40 completed connection of the control and supervisory lines over the first selecting relay is accomplished before it is possible to complete a circuit through the succeeding 45 selecting relay.

As further protection against possibly making incorrect selections, the control and supervisory line, it will be noted, are maintained disconnected from the selecting relays 50 during each stepping operation and are not again completed until the check impulse indicates that the selection has been correctly and properly made.

It will be noted that the second drive impulse was of the same polarity and over the same line, and, therefore, identical with the first drive impulse. Therefore, it is quite possible that the wrong selecting relay may be energized. However, the check impulse just traced is completed through the contacts of the two selecting relays at the office and at the substation and is of the opposite polarity from the check impulse traced above for the first selecting relay. The combination 60 of the check and drive impulses are in-

dividual for each pair of equivalent selecting relays at the office and at the substation. That is, for each selecting position, a drive and check impulse of a predetermined polarity and over a predetermined line individual to that selecting position is completed.

If relay #1 at the office and selecting relay #2 at the substation were to be energized, this check impulse would not be completed. It will be noted that the check impulses are completed over the third and fourth contacts of the various selecting relays. A study of the disclosure will show that the third contact of the first selecting relay at the office is connected to the winding of relay 228 and battery, whereas the third contact of the first selecting relay at the substation is connected to ground. The check impulse, therefore, has energy from battery at the office to ground at the substation.

On the other hand, the third contact of the second selecting relay at the substation is connected to the winding of relay 324 and battery to ground. If, therefore, the second selecting relay at the substation were energized simultaneously with the first selecting relay at the office, no energizing circuit would be completed for the check impulse.

Not only are impulses of different polarity employed to distinguish the various check impulses, but also a change in the signalling line over which the impulse is to be transmitted. The check impulse traced above not only passes through the third contact of the selecting relay but also through the fourth. While the third contact, as explained above, determines the polarity which is to be transmitted, the fourth contact determines the line over which this impulse shall be transmitted.

In the case of the first two selecting relays, since the polarity is reversed, as indicated above, there is no need to change the signalling line, and the fourth contacts of the two selecting relays are multiplied and connected over the supervisory line.

If the check impulse traced above is properly completed by reason of the correct energization of the selecting relays at the office and at the substation, the check relay 227 is energized. The energization of the relay 227 completes an energizing circuit for the relay 226 over the armature 280.

The energization of the relay 226 completes a locking circuit for itself over armatures 277 and 275 and, at the same time, an energizing circuit is completed for the relay 229, as described above.

The energization of the relay 229 switches the control and supervisory line to their operating positions. These operations are identical to those described in connection with the first selecting-relay operation.

Similarly, at the substation, the energization of the relay 325 over the check circuit traced above completes an energizing circuit

- for the relay 326 over the circuit traced above, and the energization of the relay 326, in turn, completes an energizing circuit for the relay 323, as traced above.
- 5 The energization of the relay 323 switches the control and supervisory lines 298 and 299 from their checking to their operating positions. The control and supervisory circuits are now again completed.
- 10 If the stop key has not been pulled out at the second selection position, the drive circuit is again opened, the signalling lines are again switched to their check positions and the drive line thereupon again closed for the third drive impulse. This impulse is identical with that traced for the first two. When, however, the third selecting relay is energized, the check impulse transmitted is completed from ground through the battery, the winding of relay 228, the third contact of the relay 213, back contact and armature 270, the winding of the relay 227, armature 281 and its back contact, the fourth contact of the relay 213, back contact and armature 283, the front contact and armature 286, over the conductor 298, armature 366 and its front contact, armature 369 and its back contact, the fourth contact of the third selecting relay 318, back contact and armature 372, the winding of the relay 325, the third contact of the selecting relay 318 to ground.
- 15 This check impulse, upon comparison with the first check impulse, will be found to be of the same polarity. However, it will be noted that this impulse is transmitted over a different conductor. This particular check circuit can only be completed if the third selecting relay at the office and the third selecting relay at the substation are energized. Should 20 selecting relay #3 at the office and relay #4 at the substation, or any other non-equivalent combination of selection relays be energized, this circuit would not be completed. If the check impulse is correct, the energy transmitted will operate the relays at the office and at the substation for switching the signalling lines to their operating positions, as has been described in detail above.
- 25 When the fourth stepover relay 205 energizes, an energizing circuit is completed for the relay 224 over a circuit from ground through battery, the winding of the relay 224, front contact and armature 247, and back contact and armature 265 to ground. The 30 energization of the relay 224 reverses the connection of the winding of the relay 225 from battery to ground at armature 273 and its front contact.
- 35 At the substation, upon the energization of the fourth selecting relay, an energizing circuit is completed for the relay 328 from ground through battery, winding of the relay 328, front contact and armature 352, conductor 392, conductor 497, and back contact and armature 385 to ground.

The energization of the relay 224 at the office and relay 328 at the substation, as described above, reverses the polarity of the drive impulse from battery at the office and ground at the substation to battery at the 70 substation and ground at the office. It will be noted that the first four selecting relays are energized by drive impulses of the same polarity. Each selection, however, is identified or checked by an impulse, individual to that 75 selection, either by a different polarity or by a different transmission line. Thus it may be said that each selecting relay has been operated by a code, since two impulses, both of which must be of the correct polarity and over 80 the correct line, are transmitted before a selection was completed.

The selecting relays from 5 to 8 are now energized in the manner described above in connection with the first four selecting relays 85 except that the polarity of the drive impulse is reversed. At each energization of a selecting relay, a check impulse is transmitted in exactly the same manner as described in detail above to identify the selection either by 90 polarity or signalling lines over which the impulse is transmitted.

Upon the energization of the eighth switch-over relay 208 at the office, the energizing circuit for the switchover relay 224 is opened 95 at armature 256. Similarly, the energization of the eighth switchover relay at the substation opens the energizing circuit of the relay 328.

The deenergization of the relay 224 at the 100 office and relay 328 at the substation restores the drive circuit to its original condition, and the ninth and tenth selecting relays are energized by drive impulses which are like those which energized selecting relays 1 to 4.

A further result of the energization of the eighth selecting relay is to complete an energizing circuit for the relay 231, from ground through battery, the winding of the relay 231, 105 the front contact and armature 256, the back contact and armature 265 to ground.

At the substation, the energization of the eighth selecting relay 303 completes an energizing circuit for the relay 321 from ground through battery, winding of the relay 321, 115 the front contact and armature 340, conductor 392, conductor 497, and back contact and armature 385 to ground.

The energization of the relays 231 and 321 functions to transfer or switchover the 120 conductors 299 and 398. The drive impulse, it will be recalled, was transmitted over the conductor 398. As a result, however, of the above-described switching operation, conductor 398 will now function for the ninth and 125 tenth selection as the supervisory line and conductor 299 which formerly functioned as a supervisory line, now is the drive line.

The next drive impulses, while of the same polarity as those which energized the first 130

four selecting relays, will now be transmitted over the conductor 299 and over the front contact of armatures 290 and 365 to the line drive relays 225 and 327, as traced before.

The check impulse for the ninth and tenth selecting relays will be transmitted over the conductor 398. As is clear from the above description, no two selecting relays have the same combination. This code can be continued by employing the conductor 398 as the supervisory line and the conductor 299 as the drive line for the next eight selecting relays, whereupon, the control line can be switched with the drive line in the same manner as described in detail above, so that the drive impulses are transmitted over the conductor 298, and the conductor 398 functions as a control line. This coding can be continued to a very large number of selecting relays, so that no two selecting relays are operated by the same combination of impulses.

In the present instance, it has been assumed that the dispatcher desires to operate the circuit breaker 430 to its closed position. In order to accomplish this, he will operate the stop key 151 to close its right-hand contact and operate the individual operating key 150 to position the key for closing the circuit breaker.

As a result of the operation of stop key 151, the circuit formerly traced through the stop key for energizing the relay 223 in order to open the drive circuit is not completed at this time, and the drive circuit remains closed, thereby stopping the relay chain from further stepping.

The dispatcher will now operate the master key 167 to its closed position and maintain it in this position until the correct supervisory signal, indicating that the circuit breaker has closed in accordance with his operations, is received.

Should the dispatcher open the master key before the signal is received, the apparatus is restored to normal without performing the operation, as will be described in more detail hereinafter.

After the selection has been made, a code of impulses is transmitted over the line-operating chain of relays, both at the office and at the substation, for closing the circuit breaker. A different code is employed for tripping the circuit breaker. This arrangement for operating the circuit breaker as a selector by means of a code is called "operation control".

It is an essential part of a supervisory control system inasmuch as it overcomes one of the chief difficulties experienced in employing a synchronous relay system, namely, the sensitiveness of such a system to electrical disturbances from extraneous sources.

It is, of course, possible to so operate the

synchronous system that as the line shall be switched synchronously at both ends, direct circuits are completed at each position to apparatus units without the use of a further code of impulses for actual operation.

By employing the code arrangement, which is about to be described, surges coming on during the selecting period have no effect upon the apparatus units, since it requires not only that a complete and correct selection be made for operating the unit but also the transmission of the proper code thereafter.

In this case, five impulses, three over the control line and two over the supervisory line, for changing the polarity are transmitted for closing the selected circuit breaker, while three impulses are transmitted for tripping the circuit breaker.

The relays 104 to 113 are the operation-control relays located at the office, and the relays 402 to 409 the relays located at the substation for receiving operation-control code signals.

The code that is to be transmitted is determined by the particular relay 107 or 105 energized. Energization of the relay 107 causes the transmission of five impulses for closing the circuit breaker, and the energization of the relay 105 transmits three impulses for tripping a circuit breaker.

In this instance, since it is assumed that the circuit breaker is to be closed, the individual key has been operated to energize the relay 107 over a circuit from ground through battery, the winding of relay 107, the closed contact of the key 150, conductor 180, the sixth contact of the selecting relay 211, conductor 195, contact of the master key 167, conductor 194, armature 276 and its front contact, back contact and armature 279 and the front contact and armature 275 to ground. It will be noted that this circuit is completed over the front contact of the line-drive relay 225. The circuit is also completed over the front contact of the check relay 226. This circuit, therefore, cannot be energized unless the proper check circuit has been completed and the drive line closed.

Energization of relay 107 completes an energizing circuit for relay 104 from ground through battery, winding of relay 104, back contact and lower armature of relay 113, front contact and armature 132 and over conductor 194 to ground as traced above.

The energization of the relay 226 completed the first operation control impulse over the control line from positive battery at the office to negative battery at the substation, the circuit being completed from ground over the fifth contact of the selecting relay 211, conductor 181, the right-hand contact of the stop key 151, the armature 136 and its back contact, back contact and armature 139, the upper contact of the key 167, conductor 193, the front contact and arma-

ture 283, front contact and armature 286, conductor 298, armature 366, and its front contact, armature 369 and its front contact, conductor 494, and through the winding of the relay 406, armature 450 and its back contact and battery to ground.

The energization of the relay 406 at the substation completes an energizing circuit for the relay 404 from ground through battery, winding of the relay 404, front contact and armature 446, conductor 495, armature 374 and its back contact, front contact and armature 382, front contact and armature 379 to ground. The relay 404, which is a slow-release relay, energizes and remains closed during the succeeding periods of impulses. A further result of the energization of the relay 406 is to complete an energizing circuit for the relays 402 from ground through battery, winding of the relay 402, back contact and armature 449, front contact and armature 447, front contact and armature 442, and over conductor 495 to ground, as traced above.

25 The energization of the relay 402 completes an energizing circuit over the supervisory line from positive battery at the substation to negative battery at the office. This circuit is completed from ground over the conductor 495, armature 442 and its front contact, armature 448 and its back contact, armature 454 and its back contact, front contact and armature 437, conductor 493, front contact and armature 370, front contact and armature 367, armature 364 and its back contact, supervisory line 299, back contact and armature 289, armature 287 and its front contact, armature 284 and its front contact, conductor 192, armature 124 and its front contact, through the winding of the relay 108, armature 140 and its back contact, to battery and ground.

45 The energization of the relay 108 at the office completes an energizing circuit for the relay 109 from ground through battery, winding of relay 109, back contact and armature 142, front contact and armature 133, front contact and armature 132 to ground over the conductor 194.

50 The energization of the relay 109 opens the originally traced impulse circuit over the control line at armature 136. The opening of the control line deenergizes the relay 406 at the substation which, in turn, completes an energizing circuit for the relay 407 from ground through battery, winding of relay 407, back contact and armature 439, front contact and armature 436, back contact and armature 447, front contact and armature 442 to ground over the conductor 495, as traced above, and also completes an energizing circuit for relay 405 from ground through battery winding of relay 405, front contact and armature of relay 404, back contact and armature 446 to ground over conductor 495.

The energization of the relay 407 at the substation opens the originally traced supervisory impulse at armature 448 and completes a locking circuit for itself over this armature from ground through battery, winding of the relay 407, front contact and armature 448, front contact and armature 442 to ground over the conductor 495. The opening of the supervisory line deenergizes the relay 108 at the office which, in turn, completes an energizing circuit for the relay 111 from ground through battery, winding of the relay 111, back contact and armature 146, back contact and armature 134, and front contact and armature 137 to ground as traced above.

75 The energization of the relay 111 completes an energizing circuit for itself over the front contact and armature 143, armature 127 and its back contact to ground over the circuit traced above.

80 The energization of the relay 111 completes an energizing circuit for the relay 110 from ground through battery, winding of the relay 110, front contact and armature 141, back contact and armature 147 and over conductor 194 to ground.

85 The energization of the relay 110 completes the third operation control impulse over the control line from negative battery at the office to positive battery at the substation, the circuit being completed from ground through battery, armature 144 and its back contact, front contact and armature 139, upper contact of the master key 167, conductor 193, front contact and armature 283, front contact and armature 286, conductor 298, armature 366 and its front contact, armature 369 and its front contact, conductor 494, and through the winding of relay 406, armature 450 and its front contact to ground over conductor 495.

90 The energization of the relay 406 completes an energizing circuit for the relay 403 from ground through battery, winding of the relay 403, back contact and armature 453, front contact and armature 449, front contact and armature 442 to ground over the conductor 495.

95 The energization of the relay 403 at the substation completes a locking circuit for itself from ground through battery, winding of the relay 403, front contact and armature 438, front contact and armature 442 to ground over the conductor 495 and completes the fourth impulse over the supervisory line from negative battery at the substation to positive battery at the office, this circuit being completed from ground through the battery, armature 443 and its front contact, armature 440 and its front contact, armature 445 and its front contact, armature 451 and its back contact, armature 454 and its back contact, front contact and

5 armature 437, conductor 493, front contact and armature 370, front contact and armature 367, armature 364 and its back contact, conductor 299, back contact and armature 289, armature 287 and its front contact, 70 armature 284 and its front contact, conductor 192, the front contact and armature 124, and through the winding of the relay 108, armature 140 and its front contact, back 75 contact and armature of the relay 106 to ground over conductor 194.

10 The energization of the relay 108 completes an energizing circuit for the relay 112 from ground through battery, winding of the 75 relay 112, front contact and armature 142, front contact and armature 133 to ground, as traced above.

15 The energization of the relay 112 completes and energizing circuit for itself over the front contact and armature 145. The energization of the relay 112 opens the third operating control impulse over the control line at armature 144. As a result, the relay 406 is deenergized at the substation and completes an energizing circuit for the relay 408 from ground through battery, winding of the 80 relay 408, front contact and armature 439, front contact and armature 436, back contact and armature 447, front contact and armature 442 to ground over the conductor 495.

20 The energization of the relay 408 completes a locking circuit for itself over the front contact and armature 452 and over the front contact and armature 442 to ground over the conductor 495. A further result of the energization of the relay 408 is to open the fourth operation control impulse over the supervisory line at armature 451 and to 85 prepare an energizing circuit for the relay 409 at armature 453.

25 The opening of the supervisory line at the substation deenergizes the relay 108 at the office. The deenergization of the relay 108 at the office completes an energizing circuit for the relay 113 over the circuit from ground through battery, winding of the relay 113, front contact and armature 146, back contact and armature 134, and front 90 contact and armature 137 to ground over the circuit traced above.

30 The energization of the relay 113 completes a locking circuit over the armature 149 and its front contact. A further result of the energization of the relay 113 is to complete the fifth operation control impulse from negative battery at the office over the control line to ground at the substation, this circuit being completed from ground 95 through battery, the armature 148 and its front contact, front contact and armature 139, the upper contact of the master key 167, conductor 193, front contact and armature 283, front contact and armature 286, conductor 298, armature 366 and its front 100 contact, armature 369 and its front contact conductor 494, through the winding of the relay 406, armature 450 and its front contact, to ground over the conductor 495.

35 The energization of the relay 406 at the substation completes an energizing circuit for the relay 409 from ground through battery, winding of the relay 409, front contact and armature 453, front contact and armature 449, front contact and armature 447, front contact and armature 442 to ground over the conductor 495.

40 A further result of the energization of the relay 406 is to open the energizing circuit of the relay 405. 80

45 After an interval of time, the armature of relay 405 drops to its back position. A circuit is thereupon completed for closing the circuit from ground through battery, armature 443 and its front contact, armature 440 85 and its front contact, armature 445 and its back contact, armature 455 and its front contact, conductor 491, the seventh contact of the selecting relay 320, conductor 397 and through the winding of the relay 414 to ground.

50 The energization of the relay 414 completes an energizing circuit for the solenoid 417 from the negative side of the battery, front contact and armature 466, winding of the solenoid 417 to positive side of the battery, the energization of the solenoid 417 completing an obvious energizing circuit for the operating magnet 419 over the contacts 472 and 473. The circuit breaker 420 is thereupon operated to its closed position. The closing of the circuit breaker completes an obvious energizing circuit for the relay 413 which, upon energization, in turn, completes an energizing circuit for the relay 412 over armature 485. 100

55 The energization of the relay 412 operates its armature 463 and completes an energizing circuit over the supervisory line from ground through battery, front contact and armature 463, conductor 396, sixth contact of selector 110 relay 320, conductor 490, back contact and armature 437, conductor 493, front contact and armature 370, front contact and armature 367, armature 364 and its back contact, supervisory line 299, back contact and armature 289, armature 287 and its front contact, 115

60 armature 284 and its front contact, conductor 102, armature 124 and its back contact, front contact and armature 135, conductor 186 over the seventh contact of the selecting relay 211, conductor 179, armature 116 and its back contact, conductor 188 through the winding of the relay 232 to ground.

65 The energization of the relay 232 completes an energizing circuit for the relay 101 from ground through battery, armature 295 and its front contact, back contact and armature 296, eighth contact of the selecting relay 211, conductor 178 through the winding of the relay 101 to ground. 120

The energization of the relay 101 completes a locking circuit for itself over armature 114 and opens the circuit for the lamp 153 at the back contact of 115 and at its front contact closes a circuit for the lamp 154.

The extinguishing of the lamp 153 and the illumination of the lamp 154 thus gives an indication to the dispatcher that the circuit breaker has closed in accordance with his operation.

Since the circuit which the dispatcher is to close is remotely disposed from him, he has no way of ascertaining the condition of the line at the time he operates the circuit breaker to the closed position. It may therefore, happen that he closes the circuit breaker on a short-circuit. In such case, the overload relay on the circuit breaker will immediately operate to trip the circuit breaker to its open position. This may happen while the control impulse is still completed for the operate winding of the circuit breaker so that the circuit breaker will again start to close, followed, of course, by an immediate opening thereof when it closes upon the short-circuit.

This may happen a number of times, causing what has become known in the art as "pumping". Pumping may result in serious consequences, not only to the circuit breaker but to the line which is thus being periodically closed. It is essential, therefore, to provide some means whereby, if the circuit breaker once closes and is immediately opened, it may not close again unless the dispatcher goes through the operation of tripping the circuit breaker and then again closing it by the operation of his keys.

This problem becomes difficult by reason of the fact that the pallet contacts of the circuit breaker are so arranged that the supervisory signals may be completed before the circuit breaker has completed its entire movement and been latched closed.

Means must be provided for maintaining the energy on the line a predetermined length of time in order to insure that sufficient energy is supplied to completely close the circuit breaker. As a part of this means, it is further necessary to provide an arrangement for disconnecting this source of energy in case the circuit breaker latch is closed and then tripped.

I provide a simple and very accurate anti-pumping arrangement. It will be assumed that, immediately upon the closing of the circuit breaker 420, its overload relay operates to trip the circuit breaker to its open position. As a result of this, the energizing circuit of the relay 413 is opened at the contact 421. The deenergization of the relay 413 opens the energizing circuit for the relay 412.

The deenergization of the relay 412 permits its armature 463 to drop to its back position, after a short interval of time, and a circuit is completed over the supervisory line

similar to that traced above, except that the line is connected to ground at the substation over armature 463 and is completed over armature 116 and its front contact, instead of the back contact the relay 101 being energized at this time, conductor 187 relay 233 to battery.

The energization of the relay 233 completes a shunt circuit for the relay 101 from ground over the armature 294 and its back contact, front contact and armature 296, eighth contact of the selecting relay 211, conductor 178 over the armature 114 and its front contact and battery to ground.

The relay 101 is thus deenergized and permits the armature to drop to its back position.

The lamp 154 is extinguished and the lamp 153 illuminated, thereby indicating to the dispatcher that the circuit breaker has been tripped. A further result of the energization of the relay 233 is to open the energizing circuit of the relay 110. It will be recalled that this circuit was completed over the conductor 191 and armature 297.

Upon the energization of the relay 233, this circuit is opened at armature 297. The deenergization of relay 110 opens the control line at armature 139. The opening of the control line deenergizes the relay 406 at the substation. The deenergization of the relay 406 opens the energizing circuit for the relay 404 at armature 446.

After an interval of time, the slow-release relay 404 drops to its back position and opens the operating circuit for the circuit breaker, thus preventing further closure of the circuit breaker. At the office, however, the relays 109, 111, 112 and 113 still remain energized so long as the master key is depressed so that no new operation can be restarted, since the control line is opened at relay 109 at the office.

Under these conditions, in case the master key is released, the relay 107 will still remain energized over a circuit from ground through battery, winding of the relay 107, the closed contact of the key 150, conductor 180, sixth contact of selector relay 211, conductor 195, front contact and armature 130, armature 138 and its back contact, front contact and armature 147, conductor 194, armature 276 and its front contact, back contact and armature 279, and front contact and armature 275 to ground.

In order, therefore, to release the apparatus under these conditions, it is necessary, not only to open the master key 167, but also to switch the twist key 150 to its tripped position in order that it may agree with the condition of the circuit breaker.

The circuit for the relay 107 is, thereupon, deenergized which, in turn, opens the circuit for the relays 108, 109, 111 and 113, all of which have been energized over the front contacts of armature 132 of the relay 107.

Upon the restoring of the stop key 151 to close its left-hand contact, an energizing circuit is completed for the relay 223, as traced above, which opens the drive line at armature 272, and the apparatus is thereupon stepped again from contact to contact.

Upon the energization of the last selecting relay 220, an energizing circuit is completed for the relay 221 from ground through battery, winding of the relay 221, armature 264 and its front contact, and front contact and armature 274 to ground.

The energization of the relay 221 opens the ground circuits of all the locking and energized relays at armature 265 and 266. All of the relays are deenergized, and a locking circuit is completed for the relay 221 from the ground to battery, winding of the relay 221, front contact and armature 267, back contact and armature 268 to ground.

At the substation, upon the energization of the last selecting relay, the energized circuit of all the locked relays is opened and the apparatus is restored to normal in the same manner. A circuit is thereupon completed for the relay 222 at the office and the relay 330 at the substation, as originally traced. The energization of the relay 222 at the substation opens the energizing circuit of the relay 221 which thereupon is deenergized to its original normal position.

In the foregoing, the manner in which a circuit breaker is operated to a closed position by the transmission of five impulses has been described. In order to operate the breaker to a trip position instead of to a closed position, only three impulses are transmitted as stated above. This is accomplished by operating the twist key 150 to the position shown, whereupon a circuit is completed for the relay 105 instead of for the relay 107, the circuit extending from ground through battery to the winding of relay 105, through the left hand contact shown closed in the key 150, and thence over conductor 180 as traced above in connection with the relay 107. It will be noted that relay 106 is connected in multiple with relay 105 and energized simultaneously therewith.

As a result of the energization of relay 105, a circuit is completed for the relay 104 from ground through battery, the winding of the relay 104, back contact and armature of the relay 113, the front contact and second armature of relay 105, the back contact and armature 132 to ground over conductor 194 as traced above.

From this point on, the operations are the same as described above in connection with the control impulses. It will be recalled that, after the energization of 406 in response to the first control impulse which operates invariably following the energization of relay 226, relay 404 was energized at the substation to energize relay 402 as a result of which

the second control impulse was transmitted from the substation to the office. This second impulse, it will be recalled, energized relay 108, which, in turn, energized relay 109. Energization of relay 109 opened the energizing circuit of the first control impulse, deenergizing relay 406. Relay 406 upon deenergization energized relays 407 and 405. Energization of relay 407 opened the circuit for the second control impulse circuit, to deenergize the relay 108. Energization of relay 108 energizes relay 111 which, in turn, energizes relay 110 and upon energization of relay 110, the third control impulse is transmitted over the line to energize relay 406. Relay 406, upon energization, energizes relay 403 which prepares an energizing circuit for the relay 108 as described in full above. This operation is repeated up to this point for tripping the breaker.

It will be noted at this time, however, as a result of the energization of relay 106, the circuit for the fourth control impulse which energized relay 108, is opened at the back contact of the first armature of energized relay 106, so that no circuit can be completed for this fourth control impulse. Accordingly, the relay 406 at the remote station remains energized for a longer period of time than normal and, during this period the relay 405, which as described here, is energized over the back contact and armature 446, is deenergized after an interval of time and drops its armature 445 to its back contact, completing thereover a circuit for performing an operation.

In the first described operation for closing the breaker, following the transmission of the five control impulses, the relay 409 was energized before the relay 405 deenergized and accordingly the operating circuit was completed over the armature 455 and its front contact which as traced out over conductor 491, extends to the relay 414.

In the present case, however, inasmuch as only three impulses were transmitted before the pause occurred permitting the deenergization of the relay 405, relay 409 has not been energized and accordingly the control circuit rendered effective when relay 405 deenergizes, extends over the armatures 455 and its back contact and through the contacts of the selecting relay to relay 415, which, in turn, complete an energizing circuit for the solenoid 415 to complete an energizing circuit for the tripping magnet 418.

As will now be clear from the above description, the closing is performed by five impulses during which period the relay 405 is maintained energized, it being a slow-release relay which remains energized during the short intervals between the energization of relay 406. When the impulsive stops, however, and the relay 406 remains energized for longer than a predetermined interval, a

sufficient time is provided for permitting de-energization of relay 405 and, as a result, the control circuit is completed. The control circuit, in turn, depends upon whether the relay 409 has or has not been energized; if only three impulses have been transmitted as described above, the relay 409 is not energized.

In order to restore the apparatus to normal, it is necessary to operate the stop key to its non-operative position and to open the master key 167. As a result of the opening of the master key 167, the relay 107 is de-energized which deenergizes any of the operated control relays such as 104, 108, 109, 110, 111, 112, 113, which may be energized. As a result of the operation of the stop key to its normal position, the relay 406 is deenergized, which deenergizes any of the operation control relays at the substation such as relays 402, 403, 404, 405, 406, 407. In this manner the entire apparatus is restored to normal.

Should a circuit breaker automatically operate, the apparatus is set into operation in substantially the same manner as that described in connection with a key operation. In order to illustrate this, it will be assumed that the circuit breaker 420 is automatically closed. Upon the closing of the circuit breaker an energizing circuit is completed for the relay 413 which, in turn, completes an energizing circuit for the relay 412.

Following the energization of the relay 413, but before the relay 412 is completely energized, a circuit is completed for the relay 410 from ground over armature 464 and its front contact, back contact and armature 462, armature 433 and its back contact, conductor 497 and through the winding of the relay 322 and battery to ground.

The energization of the relay 322 opens the normal holding circuit over the control line 298 and deenergizes the relays 330 at the substation and 222 at the office. Thereafter, the drive circuit operates in exactly the manner described above in connection with an operation from the office until the circuit breaker which has been operated is reached, whereupon a supervisory signal is transmitted over the supervisory line, in a manner described above.

It may happen that a second circuit breaker will be operated automatically after the circuit breaker 420 has operated but before the apparatus has been restored to normal. Means must be provided for preventing the supervisory signal for this operation from being lost. A restart circuit is provided for this purpose.

It will be recalled that one of the first relays which energized upon operation of the first selecting relay is the relay 401. The energization of the relay 401 transfers the start operation previously traced over the

armature 433 and its back contact to armature 433 and its front contact.

It will be assumed that the circuit breaker 430 closes while the selected relays are in operation and the relay 401 is energized and locked over armature 432. As in the case of the circuit breaker 420, upon the closing of the circuit breaker 430, the relay 423 is energized and, in turn, completes an energizing circuit for the relay 422. Before the energization of the relay 422, but after the energization of the relay 423, a circuit is completed from ground over armature 476 and its front contact, back contact and armature 474, armature 433 and its front contact, armature 461 and its back contact and through the winding of the relay 410 to battery and ground.

The energization of the relay 410 completes a locking circuit for itself over back contact and armature 461 and front contact and armature 458 to ground over the conductor 498. A further result of the energization of the relay 410 is to prepare an energizing circuit for the relay 411 over the armature 456. This circuit is not completed at this time because, during the operation of the selecting relay, the relay 330 is deenergized and the armature 385 is on its back contact.

After the selecting relays have completed their cycle of operation and been restored to normal, in the manner described in detail above, the relay 330 is energized. A circuit is thereupon completed from ground over armature 385 and its front contact, conductor 496, front contact and armature 456 and through the winding of the relay 411 and battery to ground.

The energization of the relay 411 completes a locking circuit for itself over armature 459 and its front contact to ground over conductor 496, and the armature 460 completes a circuit for the relay 322 over armature 457 and its back contact. This momentary circuit energizes the relay 322, which, thereupon, again starts the selecting apparatus into operation, in the manner described in detail above.

A further result of the energization of the relay 411 is to open the energizing circuit of the relay 410 at armature 461. The relay 410 is deenergized and, in turn, completes a circuit for the relay 322 over the conductor 497. The relay 322 is energized and starts the selected apparatus into operation, in a manner described in detail above.

As soon as the apparatus is started into operation, the relay 330 is deenergized and opens the locking circuit of the relay 411. The relay 411 is deenergized to open the original energizing circuit of the relay 322. The selecting apparatus now operates in the manner described above until the circuit breaker which is operated is reached, whereupon a

supervisory signal is transmitted, in the manner described in detail above.

This arrangement also provides a repeat circuit which operates every time an apparatus unit is changed to check the circuit of the unit for the dispatcher. Thus, should the dispatcher select any circuit breaker for operation and complete the operation of the breaker, the supervisory signal is received, the selecting apparatus continues through until finally restored to normal, whereupon the cycle of operations is again repeated and a second supervisory signal or check is provided for the dispatcher.

It will be recalled that it was pointed out, in the beginning of the specification, that, if the relays fall out of step, so that two non-synchronous selecting check relays are energized simultaneously, the check circuit will fail to operate. A further arrangement has been provided for immediately restoring the apparatus to normal should such a condition occur.

In order to illustrate the operation, it will be assumed that the selecting relay 211 at the office energized simultaneously with the selecting relay 319 at the substation. As has been pointed out in detail above, no checking circuit is completed, and the relay 227, therefore, fails to be energized. The lamp 171 which is energized every time the relay 227 is energized, fails to illuminate and the dispatcher is thus apprized of trouble in his set.

In order to restore the apparatus to normal, it is only necessary for him to close the key 172. An obvious energizing circuit is thereupon completed for the relay 234. The energization of relay 234 effects the opening of its armature 291 to open the drive circuit and armature 292 to remove the shunt circuit around the high resistance 292a to insert the resistance in the energizing circuit for the relays 222 and 330 which are energized when the system is in a normal non-operating condition.

At the same time armature 292b opens the negative side of the station battery circuit for all the normally non-energized relays at the dispatcher's office. In other words, the armature 292b controls or opens a bus conductor which is illustrated simply as a battery and ground connection at each relay throughout the system.

Therefore, it is evident that the opening of armature 292b, of relay 234, restores all the relays at the dispatcher's office to their normal condition.

Since the normal operating condition is attained when the drive line is closed, the drive line is normally open only for small intervals of time during the operation of the selecting relays, namely, periods during switching from one selecting relay, to the succeeding selecting relay. The energization of the relay 234, however, maintains the drive

line open at armature 291 for a period longer than is usual during the operating condition.

The energizing circuits for all the relays at the office are thereupon opened and they are restored to normal. At the substation, the relay 333 is normally maintained energized over the front contact of armature 380 when the system is in operation. During the short interval of time between the stepping operations, while the relay 327 is deenergized, relay 333 cannot be deenergized, since it is a slow-release relay.

Upon the opening of the drive line, however, and its being maintained open for a long period of time, the relay 333 drops to its back position and completes an energizing circuit for the relay 332 over the armature 391. The energization of the relay 332 effects the opening of its armature 332a to open the ground circuit of all the energized relays at the substation which are, thereupon, restored to normal.

As described hereinbefore, the opening of armature 292, of relay 234, inserted the high resistance 292a in the energizing circuit for relays 222 and 330. This causes relays 222 and 330 to drop out if they are energized or to remain out of deenergized, and relay 330 at its armature 385a opens the normal holding circuit for maintaining relay 333 closed when the drive relay 327 is not operating. This permits the relay 333 to open its armature 391, when the armature 380 of the drive relay 327 remains open for a prolonged interval of time in response to the operation of key 172.

If two selecting relays at either the office or station are operated simultaneously, the apparatus is restored to normal in the following manner. It will be assumed that relays 211 and 212 at the office are energized simultaneously. A circuit is thereupon completed for the relay 228 from ground through battery winding of the relay 228, third contact of the relay 211, and third contact of the relay 212 to ground.

The energization of the relay 228 opens the circuit of the check relay 227 at armature 281. The dispatcher is thus apprized of trouble in this apparatus. The relay 228, it should be noted, is so designed that, when energized in series with the relay 227, as is true during the checking operations, it does not get enough energy to operate its armature, but, when locally energized, as traced above, it operates its armatures to their front contacts. Similarly, the energization of any two selecting relays at the substation will complete an energizing circuit for the relay 324.

The energization of the relay 234 opens the circuits of the relays 323 and 325 to restore the apparatus to normal, in the manner described in detail above. False operations of any kind are thus eliminated.

Although I have described my invention in connection with a supervisory control system, it is obvious that this type of selecting apparatus has application to many forms of signalling systems other than supervisory control, and I do not intend to limit myself by the particular modification disclosed except insofar as set forth in the appended claims.

I claim as my invention:

- 10 1. In a supervisory control system, a first station, a second station, signalling lines connecting said stations, apparatus units at said second station, apparatus units at said first station individual thereto, selecting relays at said first and said second stations individual to said apparatus units for switching said signalling lines from unit to unit synchronously at said office and said substation, a single relay individual to each of said selecting relays for operating said selecting relays in synchronism said individual relays energizing and deenergizing sequentially with said selecting relays and means for extending said signalling lines to said selecting relays, said means being operated only when said selecting relays are energized.
- 15 2. In a supervisory control system, a first station, a second station synchronous selector relays having a normal position at said first and said second stations, a chain of relays at each station for operating said selector relays in synchronism, a drive circuit connecting said first and said second stations, means including said drive circuit for operating said chain of relays in synchronism, means whereby said drive circuit normally remains closed during synchronous operation of said selecting relays and means responsive to a prolonged opening of the drive line for restoring the selector relays to normal.
- 20 3. In a supervisory control system, a first station, a second station, apparatus units at said second station, synchronous selecting means at said first and said second stations having a normal position, means including said synchronous selecting means for selectively operating said apparatus units from said first station, a drive line connecting said first and said second stations, means for transmitting impulses over said drive line, means responsive to said impulses for operating said selecting means in synchronism each impulse affecting only one of said selecting means, means whereby said drive line is normally closed during said selective operation of said apparatus units and means responsive to a prolonged opening of the drive line for restoring the selecting means to normal.
- 25 4. In a supervisory control system, a first station, a second station, a control line and a supervisory line connecting said stations, synchronous selecting apparatus at said first and said second stations, apparatus units at

said first station, means including said synchronous selecting apparatus for selecting one of said apparatus units for operation, and means including said supervisory and said control line for transmitting a predetermined combination of impulses for operating said selected unit, the successive impulses of said code being transmitted alternately over the control and supervisory line to insure correct operations at each station.

5 5. In a signalling system, a first station, a second station, a signalling line connecting said stations, a chain of relays at each of said stations, individual relays for each of the chain relays, means for transmitting an impulse over said drive line, means responsive to said first impulse for operating the first chain relays, means responsive to the energization of said chain relays for conditioning the individual relay for energization, means responsive to the termination of the impulse for energizing said individual relay, said individual relay, upon energization, conditioning the succeeding selecting relay for energization in response to the receipt of a succeeding impulse, means responsive to each of said selecting relays for associating said signalling line therewith, manually controlled means at said first station for opening said line while said selecting relays are associated therewith and means responsive to said last mentioned means for restoring said apparatus to normal.

6. In a supervisory control system, a first station, a second station, apparatus units at said second station, synchronous selecting means at each of said stations for successively selecting said apparatus units for operation from said first station, a control line connecting said stations, a supervisory line connecting said stations, means operative following the selection of a unit for transmitting an impulse over one of said control lines, means operative following the transmission of said impulse over said control line for transmitting an impulse over said supervisory line, means responsive to said second impulse for terminating both said first and said second impulses and means responsive to a predetermined combination of said impulses for operating said apparatus unit.

7. In a supervisory control system, a first station, a second station, apparatus units at said second station, synchronous selecting means at each of said stations for successively selecting said apparatus units for operation from said first station, a control line connecting said stations, a supervisory line connecting said stations, means operative following the selection of one of said units for transmitting an impulse over said control line, means following the transmission of said impulse over said control line for transmitting an impulse over said supervisory line, means responsive to said second impulse for

terminating both said first and said second impulses, means responsive to a predetermined combination of said impulses for operating said selected apparatus unit, signal devices individual to each of said apparatus units and means including said supervisory line responsive to the operation of said apparatus unit for operating its associated signalling device.

8. In a supervisory control system, a chain of selecting relays, an individual relay for each of said selecting relays, an impulse circuit associated with one of said selecting relays, means for transmitting an impulse over said circuit for energizing said selecting relay, means including circuit connections controlled by said energized selecting relay for preparing an energizing circuit for its associated individual relay, said circuit being completed upon the termination of said impulse over said impulse circuit, and means responsive to the operation of said individual relay for disassociating said selecting relay from said impulse circuit and for associating the succeeding selecting relay with said circuit whereby said succeeding selecting relay will be energized upon transmission of the second impulse over said circuit.

9. In a signalling system, a chain of selecting relays, an individual relay for each of said selecting relays, means for transmitting an impulse to one of said selecting relays, means whereby said selecting relay is energized in response to said impulse, means including circuit connections controlled by said energized selecting relay for preparing an energizing circuit for its associated individual relay, said circuit connection being such that said individual relay is energized in response to the termination of said impulse which energized said selecting relay, and means including said connections controlled by said individual relay for preparing an energizing circuit for the succeeding selecting relay in said group whereby said succeeding selecting relay will be next energized by said impulse transmitting means.

10. In a signalling system, a chain of selecting relays, an individual relay for each of said selecting relays, an impulsing line, means for transmitting periodic impulses over said line, means for associating one of said selecting relays with said line, whereby said selecting relay is energized in response to the first of said impulses, means including circuit connections controlled by said energized selecting relay for conditioning its associated individual relay for energization, said circuit connections being closed through said individual relay upon the termination of said first impulse energizing said selecting relay, and means responsive to the energization of said individual relay for associating said second selecting relay with said impulsing circuit whereby said second selecting re-

lay is energized in response to a second impulse received over said impulse circuit.

11. In a signalling system, a chain of selecting relays, an individual relay for each of said selecting relays, an impulsing line, means for transmitting periodic impulses over said line, means for associating one of said selecting relays with said line, whereby said selecting relay is energized in response to the first of said impulses, means including circuit connections controlled by said energized selecting relay for conditioning its associated individual relay for energization, said circuit connections being closed through said individual relay upon the termination of said first impulse energizing said selecting relay, means responsive to the energization of said individual relay for associating said second selecting relay with said impulsing circuit whereby said second selecting relay is energized in response to a second impulse received over said impulse circuit, means including circuit connections controlled by said second selecting relay upon energization for preparing an energizing circuit for its associated individual relay, said circuit being such that said individual relay is energized upon the termination of the impulse which energized said second selecting relay, means controlled by the energization of said second individual relay upon the termination of said impulse for opening the energizing circuit of said first individual relay, and means including circuit connections whereby upon energization of each of said individual relays their associated selecting relays are deenergized.

12. In a supervisory control system, a first station, a second station, a control line and a supervisory line connecting said stations, synchronous selecting apparatus at said first and said second stations, apparatus units at said first station, means including said control line and said supervisory line for operating said selecting apparatus in synchronism, means controlled by said selecting apparatus operated in synchronism for selecting one of said apparatus units for operation, and means including said supervisory and said control line for transmitting a predetermined code combination of impulse conditions for operating said selected unit, said supervisory and control lines being alternately connected to transmit successive impulses of the operating code.

13. In a supervisory control system, a first station, a second station, a control line and a supervisory line connecting said stations, synchronous selecting apparatus at said first and said second stations, apparatus units at said first station, means including said control line and said supervisory line for operating said selecting apparatus in synchronism, means controlled by said selecting apparatus operated in synchronism for select-

ing one of said apparatus units for operation, and means including said supervisory and said control line for transmitting a predetermined code combination of impulse conditions for operating said selected unit, the successive impulses of said last code being transmitted alternately over said control and supervisory line in turn to insure correct operation at each station.

14. In a supervisory control system, a first station, a second station, apparatus units at said second station, relay chain synchronous selecting means at each of said stations, means for operating said synchronous selecting means at each station in synchronism for successively selecting said apparatus units for operation from said first station, a first line connecting said station, a second line connecting said stations, means operative following the selection of a unit for transmitting an impulse over one of said lines, means operative following the transmission of said impulse over said line for transmitting an impulse over the other of said lines, means responsive to said second impulse for terminating both said first and second impulses, and means responsive to a predetermined combination of said impulses for operating said selected apparatus unit.

15. In a supervisory control system, a first station, a second station, apparatus units at said second station, synchronous selecting means at each of said stations, means for operating said synchronous selecting means in synchronism for successively selecting said apparatus units for operation from said first station, a control line connecting said stations, a supervisory line connecting said stations, means including said supervisory and control lines operative following the selection of a unit for transmitting a code combination of impulses to the second station, said means being disposed to transmit different impulses of the code combination over each line, and means at the second station responsive to said code combination of impulses transmitted over both the said lines for operating said selected apparatus units.

16. In a supervisory control system, a first station, a second station, apparatus units at said second station, synchronous selecting means at said first and second stations having a normal position, means including said synchronous selecting means for selectively operating the apparatus units from said first station, a drive line connecting said stations, means for transmitting impulses over the drive line, means responsive to an impulse for operating said selecting means in synchronism, means whereby said drive line is normally closed during said selective operation of said apparatus units, and means operative in response to a prolonged deenergization of the drive line for restoring the synchronous selecting means to a normal condition, and

means operable from said first station for opening the drive line at will thereby to effect a restoring operation at any time.

17. In a supervisory control system, a first station, a second station, apparatus units at said second station, synchronous selecting means at said first and second stations having a normal position, means including said synchronous selecting means for selectively operating the apparatus units from said first station, a drive line connecting said stations, means for transmitting impulses over the drive line, means responsive to an impulse for operating said selecting means in synchronism, means whereby said drive line is normally closed during said selective operation of said apparatus units, means whereby said selecting apparatus is maintained on the selected position for said selected unit as long as the drive line is maintained closed, and means operative in the event said drive line is held open for a predetermined interval for restoring said selecting means to normal.

18. In a supervisory control system, a first station, a second station, apparatus units at said second station, synchronous relay chains at said first and second stations having a normal position, means including said synchronous relay chains for selectively operating the apparatus units from said first station, a drive line connecting said stations, means for transmitting impulses over the drive line, means responsive to an impulse for operating said relay chains in synchronism, means whereby said drive line is normally closed during said selective operation of said apparatus units, means whereby said selecting apparatus is maintained on the selected position for said selected unit as long as the drive line is maintained closed, and means operative in the event said drive line is held open for a predetermined interval for restoring said relay chains to normal.

In testimony whereof, I have hereunto subscribed my name this 28th day of July, 1927.

ALBERT L. MOREAU.
